UNITED STATES PATENT OFFICE

2,622,173

MAGNETIC BLOWOUT SYSTEM FOR HIGH-VOLTAGE CONTACTORS

Frederick Y. Grepe, Toronto, Ontario, Canada,
assignor to Canadian Controllers, Limited,
Toronto, Ontario, Canada

Application March 19, 1947, Serial No. 735,635
In Canada March 3, 1947

11 Claims. (Cl. 200—147)

1

My invention relates broadly to high voltage contactors and more particularly to an improved structure of high voltage contactor assembly.

One of the objects of my invention is to provide a construction of improved high voltage contactor system in which an effective magnetic arc blowout is associated in compact relation to an electromagnetically controlled circuit opening and closing contact system.

Another object of my invention is to provide an arrangement of arc runners capacitatively coupled to the contacts of a switching system whereby the arc may be rapidly transferred from the contactor make and break system to the arc runners and effectively dissipated.

Still another object of my invention is to provide an arrangement of magnetic system in association with arc runners which are capacitatively coupled with the main contacts of a switching system and arranged adjacent an arc dissipating structure in such manner that arcs which develop upon the opening of the main contacts are rapidly displaced from the main contacts onto the arc runners and quenched in the arc dissipating structure.

Still another object of my invention is to provide an improved and practical form of arc quenching structure which may be readily supported adjacent arc runners which are capacitatively related to the main contacts of a switching system, the arc quenching structure being readily removable and replaceable with respect to the arc runners for convenient maintenance and replacement from time to time.

Still another object of my invention is to provide an arrangement of magnetic blowout system for contactors in which a multiple winding magnetic blowout circuit is associated with the main contacts, runners and line supply circuit to the load for insuring rapid displacement of a formed arc from the main contacts to arc runners for rapid dissipation in an associated arc quenching system.

Other and further objects of my invention reside in an improved construction of magnetic blowout system for high voltage contactors which is capable of manufacture and production inexpensively on a quantity production basis as set forth more fully in the specification hereinafter following by reference to the accompanying drawings in which:

Figure 1 is a front elevational view showing the polyphase contactor assembly embodying my invention and operated by an electromagnetic actuator; Fig. 2 is a side elevational view of the

2

magnetic blowout system for high voltage contactors of my invention; Fig. 3 is a vertical sectional view taken substantially on line 3—3 of Fig. 1; Fig. 4 is a transverse sectional view taken substantially on line 4—4 of Fig. 3; Fig. 5 is a transverse sectional view taken substantially on line 5—5 of Fig. 3; Fig. 6 is a perspective view of one of the magnetic pole pieces of the magnetic blowout system employed in the apparatus of my invention; and Fig. 7 is a schematic view illustrating the capacitative relation of the arc runners and the contacts and the electrical connection of the magnetic blowout exciting windings.

15 Referring to the drawings in detail reference character 1 designates the stationary contact which is replaceably and renewably supported on conductive standard 2 by bolt member 1a. The conductive standard 2 is mounted upon insulated 20 panel support 25 which supports the magnetic blowout system, the contact system and the arc quenching system. The stationary contact 1 is directly aligned with the movable contact 3 which is renewably and replaceably supported by 25 means of bolt member 3a in arm 4 operated by the switch actuator as will be hereinafter described. The stationary contact 1 is capacitatively associated with the rear arc runner contact 6 which is renewably and replaceably supported 30 in the rear arc runner bracket 5 supported on the insulated panel structure 25. The rear arc runner bracket structure 5 is recessed at 5a to receive the renewable and replaceable rear arc runner 6 which is secured thereto by means of bolt member 6a. The upper end of the rear arc runner bracket is provided with a hook-shaped bracket extension 5b adapted to receive and support the removable and replaceable arc quenching box 35 represented generally at 26.

40 The movable contact 3 has associated therewith the movable front arc runner 17 in the form of an angular strip member which is permanently secured in position by bolt member 3a on arm 4 and capacitatively related to the front arc runner 16. The capacitative relation of the movable front arc runner 17 and the front arc runner 16 is maintained throughout the movement of operating arm 4 in establishing and breaking electrical connection between movable contact 3 and stationary contact 1. The front arc runner 16 is shaped as represented at 16a to provide an obtuse angle recess therein to serve as a rear bracket for supporting the renewable and replaceable arc quenching box 26.

55 The arc quenching box 26 is renewable and

replaceable with respect to the hook-shaped portion bracket 5b of the rear arc runner bracket 5 and is supported with respect to the rear of panel 25 by means of the hook-shaped portion 5b of bracket 5 and the transversely extending bolt member 29, the ends of which fit into the recesses 22a in brackets 22 which are supported with respect to the rear of the panel structure 25. The arc quenching box 26 comprises substantially parallel extending plate members 8 and 9 of insulation material which are spaced at their rear edges by the strip of insulation material 7 and which are spaced at their front edges by the strip of insulation material 10. The insulated plates 8 and 9 are spaced at their lower front edges by means of front arc runner 16 secured between the plates 8 and 9 by bolt members 16b. Plates 8 and 9 of insulation material form a closure for the central plate 11 of insulation material which supports the spaced arc discharge pins 12. The insulated plate 11 is supported by means of transversely extending bolt members 27 which pass through the plate members 8 and 9 and through the central plate 11 and through the gas coolers 14 and 15 and are fastened exteriorly of the plates 8 and 9 by nuts 27a.

The gas coolers 14 and 15 are formed from asbestos board or transite plates which extend horizontally across the interior of the arc quenching unit. These gas coolers are formed from arc resisting material and are disposed in the path of what amounts to an open stack formed by the space between the asbestos liners 53 and 52 which line the interior of plates 8 and 9 which is open at the base and open at the top for the free passage of air currents around the contacts 1 and 3 and around the contact 6, around the rear arc runner structure 5 and front arc runner 16 and movable front arc runner 17 and through the arc discharge pins 12 and the gas coolers 14 and 15 for discharge through the open space at the top of plates 8 and 9. The gas coolers 14 and 15 and the liners 53 and 52 are approximately $\frac{1}{8}$ " in thickness and occupy a minimum of space. The plates 8 and 9 are fastened at their front edges by bolt members 28 and at their rear edges by bolt member 29 and bolt member 29 to form the enclosed arc quenching unit. The rear closure strip 7 which serves to space plate members 8 and 9 and through which bolt member 29 and bolt member 29 transversely extend is shaped at the lower end thereof as represented at 7a to effect detachable engagement with the hook-like projection 5b of the rear arc runner structure 5 thus coacting with the engagement of the ends of bolt member 29 in slot 22a of brackets 22 in detachably mounting the arc quenching unit.

The magnetic blowout system associated with the contacts 1 and 3 consists of a pair of magnetic plate members 18 and 19 which project through slots 25a and 25b in insulated panel 25 and are supported with respect thereto by means of angle members 21 which are mounted by means of bolt members 21a on insulated panel 25. The magnetic plate members 18 and 19 are formed from magnetic laminations which are secured together and are provided with pole faces 18a and 19a which are shaped in a very special manner. The pole faces 18a and 19a are elongated in shape to effect a distribution of magnetic lines of force immediately within the area of the contact 6, rear arc runner 5 and front arc runner 16. The magnetic lines of force tend

to shift the arc which is transferred along movable front arc runner 17 at the time of break of the connection between contact 3 and contact 1 into the arc quenching system comprising pins 12. The ends of the magnetic plates 18 and 19 which project forwardly of the insulation panel 25 are interconnected by magnetic core structure 30 radially slotted at 30a to eliminate eddy current losses and fastened by bolt member 31 between the magnetic plates 18 and 19. At the position of support of the core structure 30, I provide vertically extending slots 18b and 19b in the magnetic plates 18 and 19 for eliminating eddy current losses. The magnetic core 30 supports an insulated spool member 32 which carries a pair of series connected windings 33 and 34.

The multiple winding on spool 32 consists of two series connected windings 33 and 34, the two windings being connected intermediate the terminals thereof at 35 and connected to terminal 36 which connects to the stationary contact 1. The first winding 34 on the blowout magnet is of a heavy gauge wire of a few turns to be consistent with the load which the breaker will carry and to keep normal temperatures. Winding 34 has a relatively small number of ampere turns. The second winding 33 on the blowout system consists of as many turns as desired and 20 of a smaller size wire to create a strong field for the moment of interruption. Winding 33 has a relatively large number of ampere turns. As the second winding is not in series with the load itself a light wire can be used and a proportionally larger number of turns in keeping with space and cost. The blowout windings 33 and 34 are connected in a manner that the heavy winding 34 of a few turns remains in series with the load when breaker is in the closed position 35 and the second winding 33, through the medium of the arc as a connecting link, is energized for the period when the breaker opens so that windings 33 and 34 of the blowout system are in series with each other during the period when the breaker opens, and so create a strong field when it is most needed.

The magnetic actuator for the contactor may be constructed in a variety of different ways. I have illustrated for purposes of explaining my invention an arrangement of actuating shaft 39 which is journaled in bearings supported in brackets 40 extending from the rear of panel 25. The shaft 39 has clamped thereto the angularly shiftable member 41 which resiliently supports the operating arm 4 carrying the movable contact 3. The resilient cushioning means between arm 4 and operating member 41 is represented generally at 42. The magnetic actuator for the shaft 39 is represented at 43 including the operating magnet 44 and the armature 45. Energization of the operating magnet 44 attracts armature 45 and angularly rocks shaft 39 for shifting the movable contact 3 into electrical connection with contact 1.

Electrical connection is taken from movable contact 3 and from front arc runner 16 through flexible leads 46 and 47, respectively, the leads terminating at terminal connection 48 supported on connector plate 49 carried by spacing insulator 50 extending from the rear of panel 25. Electrical connection is made to movable contact 3 and front arc runner 16 through lug 51 secured to connector plate 49.

As contact 3 moves away from contact 1 an arc is formed. The action of the flux produced

by the few turn coil 34 is to lift the arc from contact 1 to contact 6 and from contact 3 along runner 11 to runner 16. When the arc is transferred from contact 1 to contact 6 the many turn coil 33 on the blowout coil is connected in series with the few turn coil 34 so producing an intense field which moves the arc along runners 5 and 16 very rapidly and also up and into the pins 12 where the arc dissipated. The arc is thus extinguished rapidly and does not build up into an intense and destructive discharge.

The magnetic pole pieces 18a and 19a are elongated in structure and extend approximately parallel with the axis of the arc discharge between the arc runners 5 and 16. The magnetic faces 18a and 19a are elevated slightly above the general axis of the surface of the arc runners 5 and 16 sufficient to move the arc from the arc runners into the arc dissipating system constituted by pins 12 for extinguishing the arc.

The several box-like closure members which house the plates 11 carrying the arc discharge pins 12 are readily renewable and replaceable over the contacts 1 and 3. The contacts 1 and 3, contact 6, movable front arc runner 17 and front arc runner 16 are all readily renewable and replaceable. Thus maintenance of the arc quenching system may be very readily accomplished and repairs and replacements made inexpensively and with minimum shutdown time of the contactor system.

I have found the structure of my invention as set forth herein very practical for manufacture and efficient in operation. I realize however that changes may be made in the details of the structure of the apparatus and I desire that it be understood that no limitations upon my invention are intended other than may be imposed by the scope of the appended claims.

What I claim as new and desire to secure by Letters Patent of the United States is as follows:

1. In a high-voltage circuit breaker construction, a rearward main support, stationary and movable make-and-break main contacts mounted on the support, forwardly and rearwardly aligned, a stationary arc runner mounted directly on the support above the stationary main contact and independently of the stationary contact, a box-like arc chute detachably mounted on the support and readily removable therefrom, and comprising opposite spaced side walls depending below and at opposite sides of the main contacts and stationary arc runner, an arc runner mounted upon and between the chute side walls and above the movable contact and removable in unison with the arc chute, an arc cooling structure secured to and within the arc chute walls substantially filling the arc chute above the runners, a blowout magnet comprising pole pieces extending forwardly from the main support along the opposite side walls and outside the arc chute and supported stationarily by the main support independently of the removable arc chute, and embracing therebetween the contacts and arc runners.

2. In a high-voltage circuit breaker construction, a rearward main support, stationary and movable make-and-break main contacts mounted on the support, forwardly and rearwardly aligned, a stationary arc runner mounted on the support above the stationary main contact, a box-like arc chute detachably mounted on the support and readily removable therefrom, and comprising opposite spaced side walls depending

below and at opposite sides of the main contacts and stationary arc runner, an arc runner mounted upon and between the chute side walls and above the movable contact and removable in unison with the arc chute, an arc cooling structure secured to and within the arc chute walls substantially filling the arc chute above the runners, a blowout magnet comprising pole pieces extending forwardly from the main support along the opposite side walls and outside the arc chute and supported stationarily on the main support independently of the removable arc chute, and embracing therebetween the contacts and arc runners, the arc runners having arcing portions generally aligned at a rearward, upward, inclination, and the pole pieces of the magnet having mutually confronting elongated inwardly extending pole portions substantially opposite to and parallel with the aligned arcing portions of the runners.

3. In a high-voltage circuit breaker, a pair of main contacts, arc runners associated respectively with and above the main contacts and separated therefrom respectively by air gaps, an arc blowout magnet comprising a core and a winding on the core and magnet pole pieces at opposite sides of the contacts and runners receiving flux from the core, arranged to cause the arc drawn initially between the main contacts to rise and leave both main contacts and transfer completely from the main contacts to the arc runners when the winding is energized and the main contacts open; the winding being in two parts, one part being connected to be in series with the circuit to be broken and with the main contacts and with the arc therebetween, the two parts being connected to be in series with each other and with the main circuit to be broken and with the two arc runners and the arc therebetween when the arc has completely transferred to the runners.

4. In a high-voltage circuit breaker, a pair of main contacts, arc runners associated respectively with and above the main contacts and separated therefrom respectively by air gaps, an arc blowout magnet comprising a core and a winding on the core, and magnet pole pieces at opposite sides of the contacts and runners receiving flux from the core, arranged to cause the arc drawn initially between the main contacts to rise and leave both main contacts and transfer completely from the main contacts to the arc runners when the winding is energized and the main contacts open; the winding being in two parts, circuit connections causing one part of the winding to be energized alone by the main circuit current while the main contacts are closed and while the arc bridges them after they open, and causing both parts to be energized in series by the main circuit current when the arc has transferred to the arc runners, and current flow between the main contacts has ceased.

5. In connection with a circuit breaker of the type comprising an arc chute having therein main contacts, arc runners above the main contacts respectively, and transverse arc cooling structure above the arc runners; the method of breaking an arc drawn initially between the main contacts, which includes producing a magnetic field transversely of the arc which has an upper portion stronger than the lower portion subjecting the arc to the lower magnetic field portion to cause the arc to rise and form on the arc runners and become elongated thereon, and subjecting the rising elongated arc on the arc runners to a

stronger upper magnetic field portion to force it upwardly into the arc cooling structure.

6. The method of rupturing an arc drawn between circuit breaker contacts upon opening of the contacts to a predetermined distance, which includes: producing a magnetic field transversely of the arc which has an upper portion stronger than the lower portion subjecting the arc to the lower magnetic field portion to cause it to rise; causing the feet of the arc to separate to a greater distance apart than the distance between the contacts to elongate the arc; abruptly still further increasing the strength of the upper portion of the magnetic field and subjecting the elongated arc thereto to cause it to be forced upwardly; and subtracting heat from the upwardly forced elongated arc and splitting the arc to extinguish the arc.

7. A magnetic blowout system for high voltage contactors comprising a pair of circuit opening and closing contacts one of which has a generally horizontal path of movement into and out of contacting relation with the other, an arc dissipating structural system arranged above said contacts with its lower termination above the contacts, a magnetic system including a pair of elongated pole pieces extending longitudinally along opposite sides of said contacts, a pair of rib-like magnetic pole portions on the respective magnetic pole pieces, extending longitudinally thereof and mutually confronting each other, said pole portions being disposed above the said contacts and generally parallel to the horizontal path of movement thereof adjacent to the lower termination of said arc dissipating system for magnetically forcing an arc, established between and rising from said contacts upwardly into said arc dissipating system.

8. A magnetic blowout system for high voltage contactors comprising a pair of circuit opening and closing contacts one of which has a generally horizontal path of movement into and out of contacting relation with the other, an arc dissipating structural system arranged above said contacts with its lower termination above the contacts, a magnetic system including a pair of pole pieces extending along opposite sides of said contacts, a magnetic pole portion on each of said magnetic pole pieces extending toward each other, said pole portions being elongated and disposed above the said contacts and extending generally parallel to the path of movement of said one of said contacts and adjacent to the lower termination of said arc dissipating system for magnetically forcing an arc, established between and rising from said contacts upwardly into said arc dissipating system.

9. A magnetic blowout system for high voltage contactors comprising a pair of circuit opening and closing contacts one of which has a generally horizontal path of movement into and out of contacting relation with the other, a pair of arc runners, each disposed above one of the said contacts, an arc dissipating structural system arranged above said contacts with its lower termination above the contacts and adjacent to the runners, a magnetic system including a pair of magnetic pole pieces extending along opposite sides of said contacts for magnetically causing an arc drawn on the contacts to rise and transfer to the arc runners, a magnetic pole portion on each of said magnetic pole pieces extending toward each other, said magnetic pole portions being elongated and disposed above the said contacts and extending generally parallel to the path

of movement of said one of said contacts and adjacent to said runners and to the lower termination of said arc dissipating system for magnetically forcing the arc on the runners upwardly into the arc dissipating system.

10. A magnetic blowout system for high voltage contactors comprising a generally vertical arc chute, a pair of circuit opening and closing contacts in a lower part of the arc chute, one movable relative to the other in a substantially horizontal path, an arc dissipating system in an upper part of the arc chute, and above the contacts, a magnetic system including a pair of elongated pole pieces on the outside of the arc chute extending longitudinally along opposite sides of said contacts, a pair of rib-like magnetic pole portions on the respective magnetic pole pieces extending longitudinally thereof and mutually confronting each other, said pole portions being elongated and being positioned opposite the lower part of the arc dissipating system, and above the contacts generally parallel to the horizontal path of movement thereof, an arc runner connected with the movable one of said contacts, separate stationary arc runners associated respectively with the contacts and above them and below the arc dissipating system.

11. A magnetic blowout system for high voltage contactors comprising a pair of circuit opening and closing contacts, an arc runner electrically associated with each of said contacts and above it, an arc dissipating system above said arc runners, a magnetic blowout system including a pair of magnetic pole pieces extending along opposite sides of said contacts and said arc runners and the lower part of said arc dissipating system, electric circuit means connected to the contacts and arc runners and comprising winding means for magnetically energizing the pole pieces, the pole pieces formed to subject an arc drawn on the contacts to distributed flux to move the arc upwardly and effect its transfer to the arc runners and formed to subject the transferred arc to concentrated flux to force it into the arc dissipating system.
